GOLF TRAINING DEVICE

Luis W. Alvarez, Berkeley, Calif., assignor to Gaiher and Company, San Francisco, Calif., a partnership

Application November 2, 1953, Serial No. 389,586

9 Claims. (Cl. 273—186)

This invention is directed to golf training devices. The principal purpose of a device of such character is to enable the golfer to check visually on his swing with respect to the line of club movement relative to the ball to be impacted and also with respect to the velocity of club head motion as the ball is impacted. Information of such conditions make instantly available, in a training device, knowledge of the flight path and distance to be travelled by a golf ball if the golfer's swing in play could be made to coincide with that exhibited in practice.

In a preferred embodiment of the invention, as it will be described herein, apparatus is provided whereby the golfer, as he swings the club head to contact a ball, either real or simulated, is able to observe a series of images of the club head, as if arrested, in various positions as it is moving along the path of swing to the ball and during at least a part of the follow-through. By such an arrangement it is possible for the golfer to observe during the course of the swing the club head position as it approaches and leaves the position whereat the ball would be contacted. In this way direct observation may be made during the course of the golfer's normal swing of the club head without any lifting of the head which would tend to defeat a so-called "good" swing. In fact, use of the device encourages "keeping the head down" so that observations can be made. Such observations make it possible to determine whether the club face, at the instant of impact, happens to be normal to the intended direction that the ball shall take in flight or is held in an "open" or "closed" position. It is also possible to determine, by the invention herein to be set forth, whether the golf ball actually would be contacted at the center of the club head face or at the heel (shank) or toe thereof. In addition, direct observation during the course of the swing may be made of the precise path of the club head movement relative to an optimum swing line and concurrently with this there may be had an indication of the club head velocity in the region of impact with the ball.

As the invention is constituted, the ball, which is to be the target toward which the golfer is swinging the club, may be either real or simulated. If simulated the ball may be exemplified by an image of a ball at the desired impact point or it may be another appropriate form of indication toward which the club head is swung. As a guide to determine the optimum swing path along which the club head is to move an appropriate strip may be positioned to indicate both the desired optimum line of swing and the line of ball flight. A series of light-sensitive phototubes is positioned in the region of ball contact to extend both along and parallel and adjacent to the swing path in the region of ball impact. The phototubes are preferably illuminated during the course of the operation of the trainer device in such a way that the continuous illumination is interrupted at the instant the club head moves through the light path between the source and the phototube.

According to one form of operation, the interruption of light upon each successive phototube by the golf club

2

moving through the successive light beams causes a trigger pulse to be developed by an appropriate pulsing circuit therewith associated. The developed pulse causes a lamp (generally known as a "stroboscopic" lamp) associated with the phototube to flash. Thus, as a club head is swung in front of the several phototubes the lamps are flashed in succession. The brilliance of the flashing lamps is sufficient to illuminate the club head and to produce a series of positionally arrested images thereof while the club head is in its lowest position of arc of swing, generally corresponding to its ball impact region toward which the golfer's eyes are directed at all times during the swing. The flashing illumination of the relatively intense light sources illuminating the club head is adequate to create for each flash an arrested position image of the instantaneous club head position, which is seen by direct observation.

The controlling of the flashing of the lamps to produce light along the swing path may in one form of the operation be accompanied by an initiation into operation of a timing circuit which, through appropriate circuit arrangements, is caused to indicate on a suitable meter the elapsed time interval during which the club head, as swung, is moved between two selected points of measurement. These points, for instance, may be a point relatively close to that at which the club head is adapted actually to meet the ball in the striking operation and a selected point immediately ahead of such contact point. With such a form of control and with the distance known between the two points of observation, as well as the club weight and ball weight, it is possible, by calibrating an indicating device in terms of a struck golf ball to obtain a reading or indication exemplifying the distance to which a golf ball would be expected to be moved as a result of the particular impact velocity of the striking club head, assuming, of course, still air and standard temperature and barometric pressure, and also a standard grass of standard wetness.

In the operation, as it will be herein set forth, the position of the club head in its motion toward the ball is established without regard to time so that instantly the observer may determine the way in which the ball has been contacted.

With these thoughts in mind it will be apparent that the observer or player can determine immediately and for himself whether the club head is actually traveling in a direction normal to the desired direction of flight which should be taken by the impacted ball so that a decision can be reached at once as to whether the ball would actually adopt an optimum flight path, or by direct observation, whether the ball would be sliced or hooked, depending upon whether the golfer caused the club head to contact the ball from a direction leading from a point outside the normal swing path to the ball or from a point inside the normal swing path to the ball. These observations thus give a good idea of the actual movement of the club head in a vertical plane. Movement in the horizontal plane is, of course, readily observable by equally as precise observation, in which case it is possible to determine whether the ball would have been "topped" or, as the golfer says, hit "fat" or, and preferably, hit squarely.

With these thoughts in mind it becomes an object of this invention to provide a golf training device in which it is possible, first, to observe the precise line of club head movement toward a ball concurrently with the swinging motion of the club head and, in addition, to provide ways and means by which visual observation may be used to establish the impact point on the club head at which the club head actually strikes the ball to be moved. An additional object of the invention is that of providing appropriate circuitry for indicating the velocity at which the moving club head impacts the golf ball with a result that by appropriate meter indication and for an assumed

"normal" condition the distance to which the golf ball is moved may be established.

Other objects of the invention are those of providing ways and means by which various golf clubs may be swung to impact a golf ball and by making appropriate adjustments of the distance measuring indicator in accordance with condition departures from "normal", and the angle of tilt of the club head impacting the ball direct observation may be made of the distance to which the golf ball would be driven.

Still another object of the invention is that of providing a golf training device which, through the use of a simulated golf ball located in the swing path of the golf club, can be used indoors and still give the same indication as to the golf swing as would be had if a golf ball were actually impacted each time the club head was moved.

In addition, it is an object of the invention to provide apparatus which is sufficiently compact to be used in a home installation to insure the golfer of an adequate opportunity to practice his golf swing with the same effectiveness as out-of-doors, regardless of the climate and weather conditions.

Still another object of the invention is that of providing a form of golf training device usable by both professionals and amateurs alike with equal effectiveness and, at the same time usable by professionals as an instructing medium for improving the golf game played by amateurs as a result of making visual observations of the pupil's swing characteristic which normally occur too rapidly to be viewed by the eye and by such visual observations correct readily the swing path over which the golfer moves his club head and also insure the golfer of impacting the golf ball at the preferred position on the club head face.

Other objects are to provide a golf training device which can be manufactured cheaply and on which there is substantial freedom from operational defects and on which there need be no actual striking of any object to insure an adequate opportunity properly to train to improve the golf game played. Still other objects will be apparent from a reading of the following description and claims, when considered particularly in conjunction with the accompanying drawings of which:

Fig. 1 is a schematic illustration of the general type of unit to which this invention is directed;

Fig. 2 is a circuit diagram of the components contained within the control unit schematically represented by Fig. 1; and

Figs. 3A and 3B, respectively, are several curves to explain the circuit operation for a fast and a slow swing.

Referring now to the drawing and, first, to Fig. 1, a so-called "perfect" swing path of a golf club head (not shown) toward a real or simulated golf ball 11 may be considered to take place along the path 13, represented by the rectangle, with the club head swing moving in the direction of the arrows. The golf ball 11 may either be an actual golf ball teed at any desired point along the path or, in the alternative, the golf ball itself may be replaced by a simulated (either a real or virtual image) golf ball of which the image appears at the point 11. In a still further alternative, there may be marked or painted appropriately upon the strip 13, constituting the optimum swing path indication, an image of a golf ball which will represent that component which is to be impacted by the club head as it is moved. While the showing of Fig. 1 is on a scale which is generally grossly exaggerated, the swing path of a golf club for a right handed golfer swinging a club head at a ball 11 which would be such as to cause a so-called slice by reason of moving toward the ball from the outside in is diagrammatically designated by the path 13', while the path 13" might indicate a swing path generally looked upon as from the inside out to produce a so-called hook upon striking the ball.

The golf training apparatus essentially consists of one or more suitable light sources 15 adapted to direct the

issuing light therefrom along the indicated dash-dot paths to impinge upon suitable phototubes 17. As can be seen from the showing of Fig. 1, the light from each of the source 15 is adapted to be directed at all times to illuminate one of the phototubes 17, but any golf club head moving in the path of the light from the source to the phototube will eclipse or interrupt the infalling light upon the phototube to an extent adequate to interrupt completely the current flow therethrough or to produce a marked and noticeable change in the phototube output current. If necessary, suitable light reflectors, such as those schematically illustrated at 19, may be utilized for concentrating a greater portion of the output light from the light sources 15 than would otherwise be possible into the phototubes 17.

Still continuing the consideration of the schematic showing of Fig. 1, suffice it to say at this point that the output connections from the phototubes 17 lead into appropriate circuitry, such as that shown by Fig. 2, for instance, which is identified as the control unit 21, generally considered as in the nature of a triggered pulsing unit (of which one suitable form of circuit is shown by Fig. 2), to control the flashing of suitable stroboscopic lamps 23 of which one form is a so-called "Strobo-lux" of a type known as the SA-309, manufactured by Sylvania Electric Products, Inc. The flashing of the lamps 23 thus is initiated by the club head eclipsing or otherwise interrupting the light path from the sources 15 directed to the phototubes 17. By appropriately positioning the lamps 23 which are to be flashed under the control of the phototubes they are caused to illuminate during their flashing period the path along which the club head is adapted to move, such as that shown at 13. The result is that to all practical purposes the lamps' flashing is such that optically the club head motion is stopped at each point of illumination along the swing path within the range of location of the light source and phototubes. Consequently, when the golfer swings the club head into the path of the light from the light sources to the phototubes he is able concurrently with his golf swing to observe the actual club head movement path and position despite the rapidity of the club head motion. With but very little training, observation can be made to a degree of precision such that the golfer swinging the club is soon able to make an extremely accurate diagnosis of the actual golf swing being used merely by observing the stroboscopically illuminated club head. Consequently, with the club head moving as if to impact the ball 11, or to pass the point at which such a ball is imaged or would be positioned if actually present, and considering the several images of the club head relative to such a path, it is possible to know exactly whether the club head movement has been along a path coinciding precisely with the desired line of ball flight and whether the club head itself at the instant of impact is positioned precisely normal to the optimum swing path and whether the preferred central impact point of the club head actually corresponds to the position of the ball at the impact point or whether the ball is impacted by the club head at a position outwardly toward the club head toe or inwardly toward the club head heel.

By initiating the operation of appropriate timing circuitry concurrently with movement of the club head into the light path and utilizing such control circuitry in one of its forms as a measure of the charge present in a suitable charged storage element and by knowing the rate of charge of the storage element after the charge storage operation commences, it is possible through appropriate triggering control which initiates and stops the charging control operation to measure exactly the amount of charge which a storage element can acquire in the interval between the time the club head enters the path of illumination of one of the phototubes ahead of the point of impact and the time of actual ball impact. Based upon the assumption that if these two points are relatively close together the

club head velocity as it approaches the ball is so close to constant that the integrated value of charge over such a short time element provides substantially an approximate measure of the instantaneous velocity it is possible to translate the indication to one of actual club head impacting velocity. This will be explained more particularly in the discussion of Fig. 2, but suffice it to say at this point that on the control apparatus 21 a meter 25 may be included within the field of view of the golfer in accordance with the deflection of which there may be provided the desired indication. With proper meter calibration a translated value of ball travel distance is discernible. Such a meter may be reset by the control switch 121 following each swing motion.

In accordance with different club heads, such as a 2 iron, 5 iron and 7 iron or a 1 wood, 3 wood or 4 wood, for instance, to impact the ball 11 an appropriate related scale on the meter may be read, it being apparent that the ball travel will be partly in accordance with the elevation or angle of tilt of the impacting club head.

Considering now one illustrative embodiment of circuitry by which the features exemplified schematically by the showing of Fig. 1 may be realized, reference may now be had to Fig. 2 of the drawings.

In the showing of Fig. 2 the control units shown constitute illustratively two of five assumed such units, it being supposed for purposes of illustration that the upper unit represents the first of a series and that the lower unit represents the third of a series. According to the foregoing assumption, the lower unit depicted by Fig. 2 may be considered, for instance, as arranged so that the phototube 17 thereof is located along the swing path taken by the golf club head so as to be approximately opposite the point at which the club head would stroke a real or simulated golf ball.

Considering now, for instance, the upper of the two circuits, generally marked "A," and with it being understood that circuit "B" shown below it operates in substantially like fashion, it will be appreciated that tube operating voltage is supplied to the anode element 27 of the phototube 17 from a suitable voltage source (not shown) connected at the terminal point 29. The photoelectric cathode element 31 of the phototube 17 is preferably grounded at 33. This form of connection is one such that light falling upon the photocathode 31 produces a current flow through the phototube 17. Any current flowing through the phototube causes a voltage drop to occur across the resistor 35. The result of such a voltage drop is that the potential at the point 27 becomes negative with respect to that which would be maintained with the phototube in its darkened or unilluminated (cut-off) state so that the voltage of the source is effective at the point 37.

A suitable amplifier unit comprising the two halves of a tube, illustratively shown at 39, receives the phototube output. A suitable tube for this purpose may be one of the so-called 12AU7 type, or, in the alternative, two completely separate tubes may be employed. The grid or control electrode 41 of one of the tube sections receives the phototube output by the way of the connection made at the point 37 through the capacitor 43. Bias is obtained on the tube cathode by way of the resistor 45. The resistor element 47 provides a suitable grid leak. The left half of the tube 39 is loaded by the output resistor 49 through which operating plate voltage from the source connected at 29 is supplied.

Output voltage from the left-hand half of the tube 39 controls the potential effective at the grid or control electrode 51 of the right-hand half of the tube 39. Bias for this tube is supplied by the cathode resistor 55, with the resistor 57 providing the grid leak. Operating plate voltage is supplied by the source connected at 29 through the plate or load resistor 59. The output voltage from the right-hand half of the tube 39 is fed through the coupling condenser 61 to two separate paths of which

one is to the control grid 63 of a control or triggering tube 65, which, illustratively, may be one of the type known in the art as the 2D21, which is a gaseous discharge tube of the so-called "Thyatron" type.

- 5 The triggering tube 65 has its screening electrode 67 connected to the cathode 69 directly. Operating voltage for the plate or anode 71 is provided from the source connected at 29 by way of the tube output resistor 73. A suitable operating bias on the tube 65 is obtained from 10 a voltage source, indicated as the source -26 v. connected to terminal point 75 and to the tube grid 63 through resistor 77.
- While the range indicating circuit, later to be discussed, is to be controlled by way of the voltage available on 15 the conductor 79, constituting the second output path above mentioned, this discussion need not be entered into at this point, but it may be assumed here that the output of the tube 65 is fed through the coupling condenser 81 to the primary winding of a suitable transformer 83 20 in the secondary of which voltage amplification occurs. One end of each of the primary and secondary windings of the transformer 83 is grounded with the free end of the secondary winding being connected to a controlling electrode 85 of one of the illuminating tubes 23 which, as 25 already mentioned, may be of the type known in the art as the SA309. This tube, when triggered, serves to discharge the charge stored in a suitable condenser 87 which is connected through the charging resistor 89 to a suitable source of voltage such as the source marked 30 +700 v., for instance, shown connected at the terminal point 91. With operation of the tube 23 the condenser is discharged through the tube to flash it and so as to illuminate any object within range thereof.

Under the circumstances, it will be observed that if 35 light is striking the phototube 17 the potential at the anode thereof which is available at the terminal 37 is reduced to a minimum with a result that current flow can be considered as interrupted in the left-hand half of the tube 39. At such a time current flow occurs through the right-hand half of this tube and produces a voltage pulse effective at the grid or control electrode 63 of the tube 65 which is of sufficient magnitude to reduce its potential to an extent to carry the tube operation to a cut-off state because this voltage is available in addition to the bias 40 voltage source connected at point 75. The result is that the potential available at the tube anode 71 is a maximum and flashing of the tube 23 cannot occur. If, however, the light directed into the phototube 17 should be interrupted the reverse conditions occur and because of 45 the light interruption current flow in the phototube 17 is reduced and the potential available at the terminal point 37 rises to an extent sufficient to cause conduction through the left-hand half of tube 39 so that a consequent cut-off of current flow through the right-hand half 50 of this tube occurs. For this condition of operation the potential available to control the triggering of the grid 63 of the tube 65 rises to an extent sufficient to overcome the bias available at the point 75 and starts conduction within the tube 65 and a resultant drop in potential 55 at the anode end of the load resistor 73. This change in conduction within the tube 65 causes a pulse to be transferred through the transformer 83 to the controlling element 85 of the light source 23 to an extent such that the condenser 87 can discharge through the tube and bring about a state of illumination therein. Under these 60 conditions it will be appreciated that the potential available on the conductor 79, with interruption or decrease in the light available at the phototube 17, becomes more positive than is the case with light effective at the 65 phototube 17.

The conditions of operation in the lower section, marked "B," of the drawing comprising the lower phototube 17 and other components identified by numerals corresponding to those of the upper portion "A" of the 75 circuit with the addition of primes where possible bring

about, with an interruption or decrease in the light reaching the lower phototube 17, a flashing of the lower lamp 23 and likewise a rise in the potential available upon the conductor 79.

Should the assumed second, fourth and fifth phototubes and the triggering circuits activated thereby to control the second, fourth and fifth light sources have been illustrated, the operation would also have been like that above outlined for the circuits marked "A" and "B." Since, however, the various phototubes are arranged in such a way that the light reaching them is eclipsed in an orderly sequence as the club head is moved it will be appreciated that the lights 23 are also flashed in like sequence. Under these conditions, the illumination from the lamps 23 flashing in sequence is sufficient to illuminate brilliantly the club head serving as a light interrupting medium and effectively hold it for an instant in what appears to be an optically stationary position. This will provide then an indication to the golfer at the precise time of the swing of the exact position of the golf club head along the swing path, both with respect to the line of club head motion as it is related to an optimum swing path and as to the precise position of the club head relative to the ball, real or simulated, to be impacted as a result of the swing.

As has been suggested in the portion of this description which has preceded this explanation of the club head illumination control, another important feature of the invention is that of determining the velocity of impact of the club head upon the ball so as to furnish a basis from which the distance which the ball would move for any particular impacting club head speed may be derived. To this end it is important that the observation of club head velocity be made at substantially the precise point of ball impact because it is at that point in the swing where the club head strikes the ball to compress it and then, as a result of a rapid expansion of the compressed elastic body being effective against the moving club head, the ball takes off in its line of flight. Since, for the most part, an instantaneous observation made at the point of impact of the club head upon the ball would not be such as to insure an accurate representation of the exact velocity, this invention is so constituted that at the portion of the golf swing when the club head motion is almost precisely uniform, that is at the instant of impact and within a very short instant prior to actual impact, it is possible almost precisely to determine the actual velocity of the club head by obtaining an integrated value indicative of club head speed integrated between two limiting points. One of them may be a point of known distance along the path taken by the club head in its line of swing toward the ball to be impacted and the other may be a point substantially coinciding with the actual ball position as it is first struck.

To produce an indication of such character, if the triggering potentials available upon the conductors 79 and 79' are initiated respectively at a point a known distance ahead of the ball position, and at the ball position it can be appreciated that a measurement can be derived through an appropriate indicating circuit which will indicate what has happened in the interval of time between which the moving club head eclipses the light striking the phototube 17 which controls the triggering voltage effective upon the conductor 79 and that phototube which controls the triggering voltage available in conductor 79'. Since the voltage pulses effective on the conductors 79 and 79' are of positive polarity (as herein explained) with interruption of the light upon the related phototube 17, it will be appreciated that at all other times the polarity of the pulses is negative. Consequently, at the instant the light to the first of the phototubes 17 is interrupted the potential available upon the conductor 79 and which is applied to the control electrode 93 of the tube 95, is sufficiently positive to produce conduction therethrough. With tube 95 conducting, the voltage across the con-

denser 97, which has been charged from a suitable source, such as that marked +200 v., connected at the terminal point 99 and charging the condenser through the resistor 101, is placed across the cathode resistor 103 and, as a practical situation, is available at terminal 105. Tube 95 also receives plate voltage from the source connected at point 99. By virtue of the fact that the tube 95, which may also be a type 2D21, is carried to an operative state by a positive pulse on conductor 79 overcoming the bias of the source connected at point 75, and poled negatively relative thereto, the tube 95 will hold the form of operation established until cut-off by the removal of its plate voltage or reduction thereof to a negligible quantity so that the negative bias on the control grid restores the tube to its non-conducting state. When a positive pulse on conductor 79, sufficiently to overcome the bias of the source connected at point 75, is effective at the grid 93, the gaseous discharge tube 95 is caused to conduct. The tube then acts in such a way as to place the voltage built up across the condenser 97 effectively across the resistor 103. The result is that the potential effective at the point 105, where the cathode resistor 103 connects to the tube cathode 107, will be maintained at substantially constant value during conductivity within the tube 95. This condition will hold until the tube 95 is rendered non-conducting by a control of the nature already specified.

Under the circumstances it will be appreciated that when conductivity within the tube 95 places the voltage built up across the condenser 97 so that it is effective at the point 105, such potential is sufficient to provide the plate potential necessary to cause a current to flow through the left-hand half of tube 109. As shown by Fig. 2 of the drawings, the grid 111 and plate 113 of the left half of the tube 109 are connected together so as, effectively, to provide a diode type of connection, with the connected terminals for the tube grid and plate connected to the point 105 which provides the positive anode voltage on the left end of the tube. The voltage applied to anode-grid elements of this tube half relative to the cathode 115 is sufficient to cause this tube half to pass current which flows through this tube half and the tube cathode resistor 117 in the direction to charge the condenser 119. The current flows in a direction such that a charge builds up within the condenser in a direction which makes its upper plate positive relative to ground 33. The condenser charging continues during the conduction period of tube 95.

When a positive pulse appears upon the conductor 79 which is of a sufficient magnitude to overcome the biasing voltage applied to the grid 129 of the tube 131 from the source connected with its negative terminal turned toward the terminal point 75, it will be observed that the tube 131 immediately fires or conducts. By reason of the connection of the tube anode 133 to the positively charged terminal of the condenser 97 it will be appreciated that the condenser is short circuited by a path of minimum resistance with the result that the condenser 97 completely discharges almost instantly. The condenser discharge then reduces the plate potential on the tubes 95 and 131 to an extent such that the applied normal bias is adequate to cut off the tubes and return them to a state of substantially infinite plate resistance. The condenser 97 then is recharged through the resistor 101.

In a very short space of time (usually a few seconds using preferred circuit parameters), the condenser 97 is charged up to substantially the value of the source (shown as +200 v.) connected at the terminal point 99, so the system is again ready to operate.

When the conditions of operation as above outlined are maintained and with the charging of the condenser 119 through the left half of the tube 109, it will be apparent that the connections shown prevent the charge on the condenser 119 from flowing to ground through the resistors 117 and 103 by reason of the fact that the positive potential is maintained at the point 105. The voltage

which is produced across the condenser 119 in its charging is read on the applied vacuum tube volt meter. The volt meter is a generally familiar component and, as shown, includes the right-hand half of the tube 109 and embodies the biasing source 123 connected to the grid 125 with its negative terminal turned thereto and the positive terminal turned toward the junction of the cathode resistor 117 and the condenser 119. The volt meter also includes the plate current meter 127 and the plate current adjustment resistor 128 so that in accordance with the charging of the condenser 119 an indication is provided on the meter 127. The magnitude of the charge built up is a function of the time elapsed between that instant when tube 95 is initially caused to conduct and the time instant when the tube 131 conducts to discharge the condenser 97 and thus cut off both tube 95 and the tube 131. A switch 121, connected across the condenser 119 to short circuit it to ground, may be closed to restore the vacuum tube volt meter to a condition of zero reading after the circuit has once functioned.

From what has been stated above, it becomes apparent that the voltage developed at the point 105 will hold at a substantially constant value from the time coinciding with that upon which the gaseous tube 95 is triggered until such time as the second control gaseous discharge tube 131 is triggered. During the time period that the voltage is available at the point 105, it has also been pointed out that the left-hand section of the tube 109, which is connected to function as a diode, operates to charge the condenser 119. The value of charge acquired by condenser 119 will remain substantially constant since (with the switch 121 open) the condenser has no discharge path to ground, although as a practical matter the leakage resistance through the condenser and associated components will slowly cause the condenser to discharge, but this leakage is very small if high quality components are used. It is the voltage which is built up upon the condenser 119 that controls the reading obtained upon the vacuum tube volt meter. The closing of the switch 121 removes the charge by short circuiting the condenser to ground.

Considering these conditions, the graphical representations in Figs. 3A and 3B are presented to depict, in a measure, the conditions which obtain to measure the velocity at which the golf club head will impact the ball. Considering first Fig. 3A, there is represented the conditions which obtain with a relatively rapid swing of the golf club toward the ball. With such a swing the velocity of the club head as it strikes the ball, is very high, meaning, of course, a greater travel or flight distance for the impacted ball. The conditions depicted by the showing of Fig. 3A are such that time is assumed to be read from left to right. The upper curve is an indication of the constant pulse available on the conductor 79 to trigger the tube 95 to an operative state. This pulse develops at the time the club head eclipses the first light beam used to provide the measured indications. The operative or conducting state of tube 95 is maintained until a triggering pulse appears on the conductor 79¹, to trigger the second tube 131 to an operative state and immediately discharge the condenser 97. The pulse on the conductor 79¹ is represented by the second curve. It is spaced in time from the pulse in conductor 79 by that time elapsing between the club head eclipsing the first light beam and eclipsing the light beam controlling the development of the pulse on conductor 79¹.

The third curve down represents the voltage available at the point 105 to serve as the anode voltage of the diode section of the tube 109 to charge the condenser 119. The voltage to which condenser 119 charges is represented in the lowermost curve. As can be observed from the curve the time interval between the occurrence of a control pulse on the conductor 79 and the occurrence of a similar control pulse on the conductor 79¹ determines the time period during which the condenser charging occurs.

Consequently, the voltage acquired becomes indicative of the time elapsing between the club head entering one light control path and the time when it enters the last of the light control light beam paths. The more rapid the club head is moved the shorter will be the elapsed time between the occurrence of the pulses on the conductors 79 and 79¹, and, consequently, the less will be the charge built up upon the condenser 119. This means that the indicator reading on the meter 127 if maintained in a direct proportion to the charge may be assumed to represent the voltage on the condenser 119 and suitable calibration will then provide direct reading of ball flight distance and other related facts.

Considering now Fig. 3B, similar conditions are represented but it has been assumed that the club head swing is slow so that a greater elapsed time is depicted between the occurrence of the control pulse on the conductor 79 and the control pulse on the conductor 79¹ than for Fig. 3A. As is evident, this means that the voltage for the diode section of the tube 109 which becomes available at the point 105 is maintained for a greater period of time with the result that the condenser 119 can charge to a greater extent. This has been indicated by the lowermost curve of Fig. 3B which represents the voltage across the condenser at a value greater than that depicted for the curve of Fig. 3A.

With this showing, it becomes evident that it is possible, in accordance with the magnitude of the charge acquired by the condenser element 119 to determine not only the velocity at which the club head is moving at the instant of impact, but also through appropriate instrument calibrations the distance to which the golf ball would travel for any given condition of wind, temperature, humidity, and even wetness of the grass upon which the golf ball would come to rest.

It is, of course, apparent that numerous modifications may be made in the foregoing invention, included among which may be the manner of imaging the light sources upon the phototubes, the object toward which the golf club is adapted to be swung, the calibration of the meters to indicate the end results, and so on. These are, of course, well within the scope of the invention as herein set forth.

Having thus described the invention, what is claimed is:

1. A golf trainer for directly observing the swing path of a club head at spaced points in its movement toward contacting a ball which comprises a plurality of stroboscopic light sources arranged in sequence substantially adjacent and parallel to the swing path adapted to be taken by the club head, a normally illuminated light sensitive device connected with each stroboscopic light source said devices being also located at selected spaced points adjacent to the swing path on one side thereof and adapted to initiate an illumination of said source with an abrupt change in the instantaneous current flow in the light sensitive device, the sources of illumination for normally illuminating the light-sensitive devices being on the opposite side of the swing path from the light-sensitive devices, whereby the light paths are interrupted in sequence with movement of the golf club along said path whereby an individual swinging a golf club along the path is able to observe coincidentally with the swing and under the direct control of the swing the precise path of club head movement relative to the optimum swing path.

2. A golf trainer for directly observing the swing path of a club head at spaced points in its movement toward contacting a ball which comprises a plurality of stroboscopic light sources arranged in sequence substantially adjacent and parallel to the swing path adapted to be taken by the club head, a normally illuminated light sensitive device connected with each stroboscopic light source said devices being also located at selected spaced points adjacent to the swing path on one side thereof and adapted to initiate an illumination of said source with an

abrupt change in the instantaneous current flow in the light sensitive device, the sources of illumination for normally illuminating the light-sensitive devices being on the opposite side of the swing path from the light-sensitive devices, whereby the light paths are interrupted in sequence with movement of the golf club along said path whereby an individual swinging a golf club along the path is able to observe coincidentally with the swing and under the direct control of the swing the precise path of club head movement relative to the optimum swing path, a measuring means, means controlled by an abrupt change in the instantaneous current flow through a light-sensitive device eclipsed during an initial portion of the observed swing path to initiate operation of the measuring means, and means controlled by the abrupt change in the instantaneous current flow in a different light-sensitive device eclipsed during a later portion of the observed swing path to arrest operation of the measuring means, the operative period of the said measuring means being indicative of the club head velocity along the selected illuminated portion of the path.

3. In a golf trainer device the combination comprising a plurality of stroboscopic light sources arranged adjacent to a golf club swing path for illuminating selected regions of the path adapted to be traversed by the golf club in its striking movement relative to a golf ball, a like plurality of sequentially arranged light sensitive devices connected with said stroboscopic sources and also positioned approximately adjacent to and parallel to one side of the optimum swing path of club head movement and located generally in the region wherein the moving club head is adapted to impact the ball, means for normally illuminating each light sensitive device from the opposite side of the path of club head movement for maintaining a current flow of generally constant value through the associated light sensitive devices, the current flow through the light sensitive devices being adapted to be progressively interrupted in sequence from one to another in coincidence with the movement of the golf club along the swing path toward its impacting relationship to the striking point of a golf ball eclipsing the light to the light sensitive devices, means operating in response to the interruption of light in the sequentially arranged light sensitive devices successively to initiate an illumination of the stroboscopic light sources successively to provide illumination of the path of swing in coincidence with the club head movement for providing instantaneous direct visual observation thereof as if the club head movement had been arrested at various points in its swing path.

4. In a golf trainer device the combination comprising a plurality of stroboscopic light sources arranged adjacent to a golf club swing path for illuminating selected regions of the path adapted to be traversed by the golf club in its striking movement relative to a golf ball, a like plurality of sequentially arranged light sensitive devices connected with the said stroboscopic sources and also positioned approximately adjacent to and parallel to one side of the optimum swing path of club head movement and located generally in the region wherein the moving club head is adapted to impact the ball, means for normally illuminating each light sensitive device from the opposite side of the path of club head movement for maintaining a current flow of generally constant value through the associated light sensitive devices, the current flow through the light sensitive devices being adapted to be progressively interrupted in sequence from one to another in coincidence with the movement of the golf club along the swing path toward its impacting relationship to the striking point of a golf ball eclipsing the light to the light sensitive devices, means operating in response to the interruption of light in the sequentially arranged light sensitive devices successively to initiate an illumination of the stroboscopic light sources successively to provide illumination of the

path of swing in coincidence with the club head movement for providing instantaneous direct visual observation thereof as if the club head movement had been arrested at various points in its swing path, a timing means, means controlled by the current flow interruption through one of the light sensitive devices arranged along the swing path ahead of the assumed striking position for initiating operation of the timing means to gauge ball flight distance and means to arrest the operation of the timing means following club head movement beyond the ball striking position responsive to light path interruption at ball striking position.

5. A golf training device comprising a plurality of spaced means for independently illuminating successive points in the impact region of the swing path of a golf club moving to strike a golf ball, and a plurality of means coinciding in number with the illuminating means for triggering the spaced means in sequence to produce light flashes from the illuminating means in sequence in response to the motion of a golf club along the swing path through corresponding successive points to provide stroboscopic illumination of the club head and thereby, through visual observation, a direct indication of the club head in a sequence of space arrested positions along its path to contact the ball.

6. A golf trainer device comprising a plurality of spaced means for independently illuminating successive points in the impact region of the swing path along which a golf club is adapted to be moved to strike a golf ball and a triggering means connected with each illuminating means for initiating operation of the plurality of illuminating means in sequence in response to and coincident with the motion of a golf club relative to the successive points to reach the ball striking position, the triggering providing a sequence of illuminated points in the swing path with resultant observable stroboscopic representations of the club head at each point to permit visual observations of the instantaneous club head position relative to the swing path at each of a plurality of arrested positions in the swing path including that at which contact is had with the ball.

7. A device for measuring the impact velocity of a moving body striking a fixed object adapted to be moved as a result of such impact and for concurrently determining the path of motion taken by the said object when so moved subsequent to impact comprising a plurality of light sensitive elements positioned in substantial alignment adjacent to and in approximate parallelism to the optimum motional path along which the moving body would be adapted to move, means for continually illuminating each of the light sensitive elements from the opposite side of the path to produce therethrough a flow of current subject to alteration and interruption at times of light beam interception when a body moving along the path eclipses the light directed to the light sensitive elements, means controlled by the light sensitive elements for initiating stroboscopic illumination of each portion of the path along which the moving body is adapted to move to eclipse in sequence the light to the several linearly aligned light sensitive elements and means for causing such stroboscopic illumination to shift and progress along sequentially changing segments of the path along which the body moves until the light illuminating the last of the linearly aligned light sensitive elements has been eclipsed by the moving body, and a first control circuit connected to respond to the alteration of current flow in one of the light sensitive elements upon light eclipse thereto and adapted to be carried into operation concurrently with the eclipsing of light along the light path to the therewith associated light sensitive element located in the path adapted to be taken by the moving body to strike the fixed object, and a second control circuit for arresting the operation of the first named control circuit at a time period when the moving body would transform the fixed object into a moving object.

whereby the velocity of impact of the fixed object by contact of the moving body therewith is measured.

8. In a golf trainer device, the combination comprising a plurality of stroboscopic means for illuminating selected substantially adjacent regions of a path along which the head of a golf club is adapted to be moved to strike a golf ball, a plurality of aligned light-sensitive elements positioned approximately adjacent and parallel to the optimum path of motion of the club head and located in the region wherein the club head is adapted to impact the ball, means for continuously illuminating the light-sensitive elements from the opposite side of the path for initiating and maintaining normally a current flow of generally constant value through the light-sensitive elements, said current flow being adapted to be interrupted in sequence from one light-sensitive element to another in coincidence with the motion of a golf club head along a path between the light-sensitive elements and the illuminating means, and means responsive to an interruption in current flow through the light-sensitive elements due to the club head producing an interruption of light to initiate the operation of the several stroboscopic illuminating means in sequence and in coincidence with the golf club head motion, whereby along such illuminated path a rapidly moving golf club head may be visually observed as if arrested in its motion at progressive changing points in the region of impact and in accordance with its rate of motion therealong.

9. In a golf trainer device, the combination comprising a plurality of stroboscopic means arranged adjacent to a swing path of a golf club for illuminating selected regions thereof at a sequence of points adjacent to which the head of a golf club is adapted to be moved to strike a golf ball, a like plurality of aligned and normally illumi-

nated light-sensitive elements positioned approximately adjacent to and parallel to the optimum path of motion of the club head and located in the region wherein the club head is adapted to impact the ball, means for initiating and maintaining normally a current flow of generally constant value through each of the light-sensitive elements, said current flow being adapted to be progressively interrupted in sequence from one light-sensitive element to the other in coincidence with the motion of a golf club head to impact a ball eclipsing the illuminating light to said light-sensitive elements, means responsive to an interruption in the current flow through each of the light-sensitive elements to initiate the operation of a therewith related and connected stroboscopic illuminating means in coincidence with the timing of the golf club head motion, whereby along such illuminated path a rapidly moving golf club head may be visually observed as if arrested in its motion at progressively changing points in the region of impact, and means responsive at the start and termination of club movement within the impact region to measure the club head velocity.
